UNITED STATES PATENT OFFICE.

HERMAN W. EICHBAUM, OF LOS ANGELES, CALIFORNIA, ASSIGNOR OF ONE-HALF TO JOHN BECKMAN, OF RHYOLITE, NEVADA.

TROLLEY-POLE ATTACHMENT.

No. 908,981.

Specification of Letters Patent.

Patented Jan. 5, 1909.

Application filed March 28, 1908. Serial No. 423,851.

To all whom it may concern:

Be it known that I, HERMAN W. EICHBAUM, citizen of the United States, residing at Los Angeles, in the county of Los Angeles and State of California, have invented new and useful Improvements in Trolley-Pole Attachments, of which the following is a specification.

My invention relates to an attachment to the trolley-pole of an electric street-car, for use in the operation of electric switches, signals, etc.

The object of the invention is to provide a simple convenient means for operating signals, switches, gates, and the like, from electric cars while in motion.

The invention consists of the parts and the construction and combination of parts as hereinafter more fully described and 20 claimed, having reference to the accompanying drawings, in which—

Figure 1 is a front elevation of the invention. Fig. 2 is a side elevation thereof. Figs. 3 and 4 are diagrammatic views illustrating the electrical connections.

A represents the trolley-pole of an ordinary street-car. Fastened to this pole at the required distance from the wheel 2, say from six inches to one foot, more or less, is a cylinder 3. The cylinder 3 may be attached to the trolley-pole A by any suitable means, as the clamps 4.

5 is a piston working in the cylinder, and 6 is a piston-rod extending upward through 35 the head of the cylinder, and pivotally connected with a lever 7, which latter is fulcrumed in a bracket 8 on the cylinder. This lever arm 7 extends laterally, and at its outer end is pivotally attached the upright rod 9, 40 which has a limited oscillating movement between the spring-plates 10 carried on the arm 7. The upper end of the stem 9 carries a contact member 11, which is designed to be raised on the actuation of the piston 5 45 into contact with a corresponding contact wire 12 stretched alongside of the main trolley-wire 14, and at suitable intervals along the line of travel of the car, wherever there is a signal or other apparatus or mechanism to be operated from the car. By having the stem 9 pivotally supported between the spring-plates 10, the roller 11 cannot bear too hard on the wire 12 when making a contact, since the springs 10 will yield suffi-

ciently to prevent breakage of the parts. 55 The weight of the parts 7—9—10—11 is such as normally to depress the contact roller 11 out of operative engagement with the section 12, and correspondingly to raise the piston 5 in the cylinder 3.

60 The top of the cylinder is connected with any suitable source of air supply, as the reservoir 15. By suitable means, represented by the controlling valve 16, air or other compressed fluid is admitted into the cylinder 3 65 on top of the piston 5, causing the latter to move downward, and correspondingly to raise the contact roller, so that whenever the latter travels over a section of wire 12 it will close an electric circuit and operate the signal 70 or other apparatus, which latter is arranged in circuit with wire 12 and roller 11; any suitable form of electrical connections being employed to produce the desired result.

75 For the purpose of illustrating the principle of the invention, I have indicated a switch 17 operated by the energizing of a suitable solenoid magnet 18. One terminal of this magnet is connected with the contact section 12, and the other terminal is in electrical contact with the track rail 19. The roller 11 on the car is in electrical contact through the electrical conductor 20 and battery 21 and the wheels on the car, with the rail 19. As long as the roller 11 is out of contact with the section 12, the circuit through the switch solenoid is broken. The moment, however, compressed air is admitted into the cylinder 3 to actuate the piston 5, the roller 11 is lifted, and when it strikes the section 12 85 90 the circuit will be closed and the switch point 17 will be operated.

95 It is manifest that the invention is applicable to operate a variety of forms of electrical mechanisms.

Having thus described my invention, what I claim and desire to secure by Letters Patent is—

1. The combination with a trolley-pole and a trolley-wire, of a contact member arranged adjacent to the trolley-wire and having electrical connections with an object to be electrically actuated, a mechanically operated contact member carried by the trolley-pole and having electrical connections through the car with the aforesaid object to be electrically actuated, and fluid pressure means for placing said contacts in the path of one

another, whereby the circuit is closed on the passing of the car.

2. The combination with a trolley-pole and a trolley-wire, of a contact member arranged adjacent to the trolley-wire and having electrical connections with an object to be electrically actuated, a mechanically operated contact member carried by the trolley-pole and having electrical connections through 10 the car with the aforesaid object to be electrically actuated, and fluid pressure means operative from the car for actuating the contact member on the trolley-pole to engage the first-mentioned contact member.
- 15 3. The combination with a trolley-pole and a trolley-wire, of a contact member independent of the trolley-wire and arranged adjacent thereto, a pivotally supported contact member carried by the trolley-pole, and fluid pressure mechanism for placing said last-named

contact member in operative position to engage the first-named contact member.

4. The combination with a trolley-pole and a trolley-wire, of a contact member arranged adjacent to the trolley-wire, a cylinder on the 25 trolley-pole, a piston in the cylinder, a lever fulcrumed to the cylinder and connected with the piston-rod of said piston, the opposite end of said lever having a contact member to engage the first-mentioned contact member on the actuation of the piston, and fluid connections for operating the piston.

In testimony whereof I have hereunto set my hand in presence of two subscribing witnesses.

HERMAN W. EICHBAUM.
